UNITED STATES PATENT OFFICE.

WILFRED T. BIRDSALL, OF MONTCLAIR, NEW JERSEY, ASSIGNOR TO WESTINGHOUSE ELECTRIC AND MANUFACTURING COMPANY, A CORPORATION OF PENNSYLVANIA.

VACUUM-TYPE CONVERTER.

1,277,365.

Specification of Letters Patent.

Patented Sept. 3, 1918.

Application filed October 9, 1915. Serial No. 54,981.

To all whom it may concern:

Be it known that I, WILFRED T. BIRDSALL, a citizen of the United States, and a resident of Montclair, in the county of Essex and State of New Jersey, have invented a new and useful Improvement in Vacuum-Type Converters, of which the following is a specification.

My invention relates to vacuum-type converters, and it has for its object to provide a device of the character described that shall be simple and inexpensive in manufacture and highly effective in operation, being especially free from short circuits and allied phenomena.

The single figure of the accompanying drawing is a perspective view of a converter embodying my invention, together with associated supply and regulating circuits.

In the operation of multi-anode vacuum-type converters, there is a tendency for current-carrying particles to migrate from one anode to another and to break down the negative-electrode reluctance of one of the anodes, thus producing short circuits. By my invention, I so design a converter that the cathode blast is interposed between two anodes which are subject to short circuiting. Furthermore, I place a small amount of gas, which is inert with respect to the material within the converter, such, for example, as hydrogen, nitrogen or argon within the container, and said gas is entrained with the cathode blast, tending to provide a rapidly moving current of gas molecules and current-carrying particles between the anodes in question. The effect of said blast is to sweep away and neutralize migratory electrons tending to pass from one anode to another, thus obviating short circuits. I am thus enabled to provide an effective shielding action without the interposition of mechanical shielding devices of the type commonly employed in the prior art.

Referring to the accompanying drawing for a more detailed understanding of my invention, I show the container of a vacuum-type converter at 1. The container 1 is provided with a pair of main anodes 2 and 3, a main cathode 4, and an auxiliary anode 5. The cathode 4 is preferably composed of vaporizable reconstructing material, such, for example, as mercury or suitable amalgams and is disposed in the lower portion of the

container 1. The anodes 2 and 3 are mounted, respectively, in opposing laterally extending arms immediately above the cathode 4. The upper portion of the container 1 is formed into a condensing chamber of considerable size, and a return tube 6 connects the upper portion of said chamber to a point near the cathode surface. The anodes 2 and 3 are connected, respectively, to the terminals of a source of alternating current 7, and the cathode 4 is connected to the mid-point of said source through a load 8, as is usual in the converter art. The starting anode 5 may be excited in any suitable manner, as, for example, by connection to a terminal of the source 7 through a current-limiting device 9. The interior of the container 1 is filled with an inert gas, such, for example, as hydrogen, nitrogen or argon, at a pressure suitable for operation in the given apparatus.

Having thus described the construction of a converter embodying my invention, the operation is as follows: upon placing the device in operation, a cathode blast is emitted from the surface of the electrode 4 and sweeps in front of the openings leading to the anodes 2 and 3 and on into the condensing chamber. Said cathode blast is made up of molecular mercury, positive ions and electrons. By an injector action, inert gas is drawn from the tube 6 and mixes with said blast, thus adding a large number of inert gas molecules to the upwardly sweeping stream. The anodes 2 and 3 may become highly heated or, for other reasons, tend to emit current-carrying particles, in the form of either positive ions or electrons. The passage of said articles to the other anode and their violent impact thereupon might result in the production of a short circuit but, in their attempted passage through the upwardly sweeping composite blast, they are either neutralized by contact with a particle of the opposite polarity or they are mechanically swept upward and prevented from passing across to the other anode. Upon reaching the cool portions of the condensing chamber, the mercury vapor is condensed and drips back to the cathode, and the inert gas returns through the tube 6 to repeat its cycle of operations.

The presence of the above described composite blast between the anodes serves as an

extremely effective shielding means, at the same time tending to distribute the heat throughout the device and thus render its dissipation a relatively simple problem.

5 Because of the complex and variable nature of said blast, I shall refer to the same in certain of the claims as composed of a "gaseous fluid", meaning thereby that it may be composed of a gas, a vapor, or mixtures of the

10 two in varying proportions, the gaseous or vaporous particles being either uncharged or conveying charges of either polarity.

While I have shown my invention in its preferred form, it will be obvious to those skilled in the art that it is susceptible of various minor changes and modifications without departing from the spirit thereof and I desire, therefore, that no limitations shall be placed thereupon except such as are

15 imposed by the prior art or are indicated in the appended claims.

I claim as my invention:

1. In a vacuum-type converter, the combination with a cathode, of a plurality of anodes disposed adjacent thereto, means for causing a cathode flame proceeding from said cathode to be projected between said anodes, and means for continuously supplying an inert gas to said flame, whereby a strong blast is maintained and current-carrying particles are prevented from passing from one anode to another, with resultant short circuiting.

2. A vacuum-type converter, comprising a container provided with a cathode, a plurality of anodes, and a condensing chamber located beyond said anodes with respect to said cathode, said container being charged with an inert gas at low pressure, whereby a cathode blast proceeding from said cathode to said condensing chamber tends to continuously entrain gas particles and sweep them along therewith, forming a

composite blast acting as a shield between said anodes.

3. A vacuum-type converter comprising a container provided with a cathode, a plurality of anodes and a condensing chamber located beyond said anodes with respect to said cathode, said container being charged with an inert gas at low pressure, and a return tube from a distant point in said condensing chamber to the neighborhood of said cathode, whereby a cathode blast proceeding from said cathode to said condensing chamber tends to continuously entrain gas particles and sweep them along therewith, forming a resultant composite blast acting as a shield between said anodes, said gas particles returning through said tube.

4. In a vacuum-type converter charged with a small amount of inert gas, the combination with a pair of electrodes, of shielding means therebetween comprising a blast of vapor and a plurality of inert gas molecules entrained therewith.

5. In a vacuum-type converter charged with a small amount of inert gas, the combination with a pair of electrodes between which an arc tends to form by the migration of electrons, of shielding means therebetween comprising a blast of vapor containing positive ions and a plurality of inert gas molecules entrained therewith.

6. In a vacuum-type converter charged with a small amount of inert gas, the combination with a pair of electrodes between which an arc tends to form by the migration of electrons, of shielding means therebetween comprising a blast of charged particles and a plurality of inert gas molecules entrained therewith.

In testimony whereof, I have hereunto subscribed my name this 29th day of September, 1915.

WILFRED T. BIRDSALL.
